UNITED STATES PATENT OFFICE.

WILLIAM M. BRITTON, OF SYRACUSE, NEW YORK.

METHOD OF AND APPARATUS FOR MAKING COTTER PINS.

Application filed December 10, 1923. Serial No. 679,602.

To all whom it may concern:

Be it known that I, WILLIAM M. BRITTON, a citizen of the United States of America, of Syracuse, in the county of Onondaga, 5 in the State of New York, have invented new and useful Improvements in Methods of and Apparatus for Making Cotter Pins, of which the following, taken in connection with the accompanying drawings, is a 10 full, clear, and exact description.

This invention relates to a method of and apparatus for making cotter pins of the split type having a head at one end as set forth in my pending application Serial Number 679,601, filed December 10, 1923, and refers more particularly to the method of establishing a twisted and offset relation between the head and shank so that the head 15 is elongated in the plane of the split.

20 The main object is to effect these relations in a simple, economical and efficient manner in practically one operation.

These pins are usually made of strips of 25 half-round wire bent or folded substantially midway between their ends around a suitable supporting form with their flat faces in juxtaposed relation, and one of the specific objects of my present invention is to 30 turn the head a quarter turn, relatively to the shank immediately following the folding operation, and while the pin is still supported upon the form and held between the pinching dies.

35 Another object is to withdraw the supporting form immediately following the turning or twisting operation and withdrawal of the pinching dies for releasing the finished cotter pin and allowing it to drop into a suitable receptacle thus leaving 40 the machine ready for a repetition of the folding and twisting operations upon succeeding strips.

45 Other objects and uses will be brought out in the following description.

In the drawings:

Figure 1 is a longitudinal vertical sectional view of a portion of a machine for carrying out the process in which the dies are shown in their normal open or starting 50 positions.

Figure 2 is a detail vertical sectional view taken in the plane of line 2—2, Figure 1.

55 Figure 3 is a detail sectional view similar to Figure 1, except that the dies are in their closed positions for the initial forming of the pin ready for twisting the head.

Figures 4 and 5 are enlarged horizontal sectional views of portions of the machine taken respectively in the planes of lines 4—4, 60 Figure 1, and 5—5, Figure 3.

Figures 6 and 7 are opposite side elevations of the completed cotter pin.

These cotter pins are usually made of half-round wire, and the process of making them consists in cutting the wire into 65 suitable strip lengths, then bending or folding each strip substantially midway between its ends around a suitable supporting form with its ends extending in the same direction and the flat sides of the opposite legs facing 70 each other, after which the legs are pressed together throughout the major portions of their lengths and close to the support, but mainly at one side of the axis of the support so as to leave one leg substantially 75 straight and tangential to the periphery of the support and the other leg in close proximity to and parallel with the straight leg thereby forming a substantial cylindrical shank and a transversely elongated head at 80 one side of the axis of the shank and in a plane at right angles to the meeting faces of the legs after which the head and shank are relatively turned or twisted a quarter turn to bring the laterally elongated and 85 offset head in a plane parallel and preferably coincident with the meeting faces of the legs or longitudinal division of the shank.

Any suitable means may be employed for 90 carrying out the various steps of this process and for this purpose, I have shown an apparatus consisting of a frame —1— having a horizontal guide —2— along which the wire as —a—, is fed endwise by hand or any other 95 suitable means against a suitable stop —3— on the frame.

The frame is provided with a relatively fixed hardened shearing edge —4— adjacent the guide —2— a distance from the stop 100 —3— corresponding to the length of wire required to form the cotter pin for cooperation with a vertically movable knife or cutter —5— carried by a plunger —6— which is reciprocally movable in a suitable guide 105 —7— in the frame —1—.

An upright sleeve —8— is journaled in the upper portion of the frame —1— for rotary movement directly over the guide —2— substantially midway between the stop —3— 110 and cooperative shearing members —4— and —5— and carries at its lower end, a horizon-

tally movable wire supporting form —9— which is preferably cylindrical and around which the intermediate portion of the wire strip —a'— is adapted to be folded or bent 5 in a manner hereinafter described, said pin being movable endwise in a guide opening —9'— at one side of the axis of the sleeve —8— a distance corresponding approximately to the thickness of the wire strips 10 —a— to permit the formation of the head of the cotter pin mainly at one side of the axis of its shank and also to allow the head of the cotter pin to be twisted about the axis 15 of the shank as will be hereinafter more fully described.

The wire —a— with its flat side at the bottom is fed endwise forwardly along the guide —2— and across the upper face of the form —9— until its forward end engages the 20 stop —3— whereupon the shearing plunger —6— is depressed to cause its knife —5— to cooperate with the shearing member —4— for severing the strip which is to form the cotter pin from the main body of the wire, 25 after which the ends of the severed strip are pressed downwardly around the form —9— to form the head and opposite legs of the shank of the cotter pin.

The means for bending the ends of the 30 wire strip around the form —9— consists of a die —10— secured to the lower end of a vertically movable plunger —11— which is guided in an opening —12— in the sleeve —8— with its axis passing through the axis 35 of the wire-supporting form —9— and therefore, eccentric to the axis of the sleeve —8—, a distance corresponding approximately to the thickness of the wire.

The die —10— is provided in its lower 40 face, with a substantially semi-circular recess —13— having its axis in the vertical plane of the axis of the wire-supporting form —9— and its radius substantially equal to the combined radii of the wire-supporting 45 form and wire so that when the plunger —11— with the die —10— thereon is depressed, the walls of the recess —13— will engage and depress the ends of the wire strip around opposite sides of the form 50 —9— thereby forming an eye in the head of the pin.

Immediately following this bending operation 55 of the wire around the form —9—, the ends of the wire strip are pressed together beneath and adjacent the pin by a pair of horizontally movable dies —14— and —14'— which are movable in suitable guides —15— in the frame —1— as shown in Figures 1 and 3.

60 The shearing plunger —6— is adapted to be depressed against the action of a retracting spring —16— by means of a hand lever —17— which is pivoted at one end by a pivotal bolt —18— to one side of the upper end 65 of the sleeve —8— at a point between the

plungers —6— and —11— and is provided with a bearing —19— adapted to be brought into engagement with the upper end of the plunger —6— when turned to a position shown by dotted lines in Figure 1, for severing the strip as —a'— which is to form the cotter pin as the free end of the lever is rocked downwardly against the action of the retracting spring —16—.

This same lever —17— is also used for depressing the plunger —11— against the action of a retracting spring —20— and for this purpose, the edge of the lever opposite the bearing —19— is provided with an additional bearing —21— engaging in a diametrical slot —22— in the upper end of the plunger and adapted to rest against a hardened bearing —23— whereby when the lever is rocked across the upper end of the plunger and depressed to the position shown by dotted lines at the right of Figure 1, the plunger —11— and its die —10— will be depressed to bend the wire strip —a'— around the supporting form —9— or to the position shown by dotted lines in the same figure, it being understood that when pressure upon the lever for operating either the plungers —6— or —11— is released, the lever and plungers will be returned by their respective springs —16— and —20—.

When the wire strip —a'— has been bent around the supporting form —9— as just described, and while the plunger —11— is still held in its depressed position, the dies —14— and —14'— are operated to pinch 95 the ends of the wire strip against each other.

The means for operating the dies —14— and —14'— consists in this instance, of a pair of bell crank levers —24— and —24'— pivoted at —25— to the main supporting frame —1— at opposite sides of the plane of movement of the plunger —11—, said levers having upwardly projecting arms provided with furcated ends adapted to engage suitable pins or bearings —26— on their respective dies —14— and —14'—, the other arms of the levers —24— being extended toward each other and connected by links —26— to a yoke —27— which in turn is pivoted at —28— to an upright rod —29—.

The lower end of this rod is connected to a pedal lever —30— by which the rod —29— may be depressed for operating the dies —14— and —14'— toward each other against the action of retracting springs 120 —31—, Figure 1.

It is desirable to operate the dies —14— and —14'— in such manner that one of the legs of the cotter pin will be left substantially straight or tangential to the adjacent side of the supporting form —9— and to press the other leg of the pin, mainly beyond the vertical plane of the axis of said supporting form so that the two flat faces of the legs are brought together leaving the 130

head of the pin elongated and offset laterally at right angles to the plane of the split or meeting faces of the legs of the cotter pin, and for this purpose the movement of the die 14' is limited by cooperative stop shoulders 32 and 32' on the die and frame respectively to cause the inner end of the die 14' to stop as soon as it has forced the adjacent leg of the cotter pin to a vertical position, while the swinging movement of the yoke 27 on the rod 29 permits the other die 14 to bend the corresponding leg of the cotter pin slightly beyond the vertical plane of the axis of the supporting form 9 to contact with the opposite leg and thereby to produce the desired offset of the head of the cotter pin.

The central portion of the lower end of the bending die 10 is slotted to receive the supporting form 9 when the plunger 11 is depressed and also to permit the walls of the recess 13 to engage the opposite sides as well as the periphery of the head as *b*, of the cotter pin *B*, Figures 6 and 7.

As previously stated, the wire-supporting pin 9 is mounted upon the lower end of the sleeve 8, and normally extends at right angles to the direction of length of the wire strip *a'*, but as soon as this strip is bent around the supporting form 9 by the depression of the plunger 11, the sleeve 8 with the die 10 and plunger 11 are rotated a quarter turn, while the shank of the cotter pin is firmly held against rotation by engagement therewith of the dies 14 and 14' whereby the portion of the cotter pin at the junction of the head with the shank will be twisted and the wider portion of the head *b* of the cotter pin will be caused to lie in substantially the same plane as the meeting faces of the opposite legs of the pin, it being understood that the axis of rotation of the sleeve 8 is substantially coincident with the axis of the shank of the folded cotter pin and that the offset portion of the head will be twisted to a plane substantially coincident with the plane of the meeting faces of the legs of the pin.

The means for rotating the sleeve 8 consists of the lever 17 and its bearing 21 engaging in the slot 22 on the upper end of the plunger 11 together with the pivoting of the shorter end of the lever to the upper end of the sleeve 8 so that while the free end of the lever 17 is depressed and the dies 14 and 14' are in their closed position, a lateral movement of the lever through an arc of substantially 90° will cause a corresponding rotation of the sleeve 8 and bending die 10 to effect a similar twist of the head of the cotter pin relatively to its shank.

This latter operation completes the for-

mation of the cotter pin around the supporting form 9 and immediately following this operation, the wire-supporting form 9 is withdrawn from the cotter pin to allow the latter to drop by its own weight 70 into an underlying receptacle not shown.

For this latter purpose, one end of the form 9 is provided with a radial projection 33 adapted to engage in a notched pawl 33' on the adjacent side 75 of the die 14' when the sleeve 8 with the die 10 and plunger 11 thereon are turned a quarter turn from their normal positions, and while the dies 14 and 14' are still in their closed positions upon the shank of the cotter pin so that as soon as the pressure upon the pedal 30 is released and the dies are withdrawn by their respective springs 31, the engagement of the notched pawl 80 33' with the projection 33 on the form 9, will withdraw said form from the head of the cotter pin and thus permit the latter to drop to the floor or any underlying receptacle.

As the plunger 14' approaches the limit of its outward movement, the pawl 33' is depressed against the action of a retracting spring 34 by engagement with the upper wall of the guide 15 thereby releasing the wire-supporting form 9 and allowing it to be returned to its normal position by a retracting spring 35.

Immediately following this retracting operation of the supporting form 9 to its normal position, the downward pressure upon the hand lever 17 is released and returned to its normal up position by its retracting spring 20 whereupon it may be turned laterally a quarter turn to its starting position to cause a similar return movement of the sleeve 8, plunger 11 and die 10 ready for a repetition 100 of the operations previously described.

In other words, following each forward movement of the wire *a* against the stop 3, the strip which is to form the cotter pin is first cut to the desired length, then bent around the form 9 by the depression of the die 10 and following which the depressed ends of the strip are pressed together to form the shank of the pin by the closing of the dies 14 and 14'.

The head of the pin is then twisted a quarter turn by the rotation of the die 10 after which the form 9 is withdrawn to allow the finished pin to drop from the machine and the operating parts are then returned to their normal positions ready for a repetition of the operation upon another strip.

I claim:

1. A method of forming split cotter pins,

- consisting in bending a strip of wire around a suitable support to form a head and opposite legs, then pressing the legs together to form the shank, and then turning the support about the axis of the shank to twist the head relatively to said shank. 5 the pin in a plane parallel with the plane of the split. 30
2. A method of forming split cotter pins, consisting in bending a strip of wire around a suitable support to form a head and opposite legs, then pressing the legs together mainly at one side of the axis of the support to form a shank and to offset the head, and then turning the support a quarter turn relatively to the shank for twisting the head at right angles to its bending plane. 10 35
3. A method of forming split cotter pins consisting in bending a strip of wire around a suitable support to form a head and opposite legs, then pressing the legs together to form a shank, and then relatively twisting the head and shank about the axis of said shank to bring the widened portion of the head in a plane parallel with the meeting faces of the legs. 20 40
4. An apparatus for making split cotter pins, having in combination, a wire bending mechanism, means for forming the head of the cotter pin, and a twisting mechanism for locating the greater width of the head of 25 45
5. In an apparatus for making split cotter pins, means for folding a strip of wire intermediate its ends to form a head at the fold, means for pressing the ends together to form the shank, and means for bringing the widened portion of the head in a plane parallel with the meeting faces of the end. 35
6. In an apparatus for relatively twisting the head and shank of a split cotter pin, a device for gripping the head, a device for gripping the shank, and means for partially rotating one of said devices relatively to the other device. 40
7. In an apparatus for making split cotter pins, a supporting form for the cotter pin blank, means for bending the blank around said form to form the head and legs of the pin, means for pressing the legs together, and means for relatively rotating the pressing means and form to effect a relative twist between the head and legs. 45 50

In witness whereof I have hereunto set my hand this 6th day of December, 1923.

WILLIAM M. BRITTON.
